UNITED STATES PATENT OFFICE.

BENJAMIN MOSER, OF BROOKLYN, NEW YORK.

LOCK.

SPECIFICATION forming part of Letters Patent No. 313,092, dated March 3, 1885.

Application filed May 1, 1884. (No model.)

To all whom it may concern:

Be it known that I, BENJAMIN MOSER, a citizen of the United States, and a resident of Brooklyn, in the county of Kings and State of New York, have invented certain new and useful Improvements in Locks, of which the following is a specification.

The invention relates to improvements in locks; and its nature and advantages will be pointed out in the detailed description herein-after presented, reference being had to the accompanying drawings, in which—

Figure 1 is a plan view (looking into its interior) of a lock embodying the invention. Fig. 2 is a vertical section on the line 1 2 of Fig. 1. Fig. 3 is a vertical transverse section on the line 3 4 of Fig. 2. Fig. 4 is a bottom face view of the button W. Fig. 5 is a view of the key, the dotted lines illustrating the relative position of the wings a when spread apart.

In the drawings, A denotes the outer casing, within which are arranged the bolts B C, one being at each side of the casing, and the two being connected adjacent to their points by the cross-bar D, the horizontal center of which is removed, forming an elongated slot E.

The points of the bolts B C are adapted to move through slots or apertures formed in the end wall of the casing A, while the rear ends of said bolts, (lettered F G, respectively,) are of suitable form and length, and are each provided with a post, H, a lug, I, and a shoulder, B'.

The posts H H serve as bearings for the ends of the spring J, which is secured at its central portion on the post K and exerts a forward tension on the bolts through the posts H H. The bolts B C are given their sliding movement, to permit or prevent the opening of the door by the arm K', which has a slot, L, in its end encircling the post H on the bolt C, and is actuated by the rotation of the knob-spindle. The bolts B C, being connected by the bar D, have a simultaneous movement.

Adjacent to the inner edges of the bolts B C are pivotally secured the oscillating levers M, the front ends of which have upon their inner edge the notches N, while the rear end of said levers M have posts O and lugs P, which

latter are on the outer edges of the levers, and arranged in convenient relation to engage the lugs I at the proper time, as hereinafter described. The rear ends of the levers M are given a tension toward the adjacent portions of the bolts B C by means of the spring Q, the central portion of which is wrapped around the post K, while its ends bear against the posts O, connected with the said levers M.

Between the front ends of the levers M is applied a bar, R, which is connected with a slide, S, located upon the outer face of the casing A by a pin, T, passing through the elongated slot V. The ends of the bar R are suitably conformed to enter the notches N, formed in the front ends of the levers M, at the proper time, and to slide therefrom when the bar is moved forward by the operation of the slide S.

The bar R and slide S may be secured at the end of their forward movement, or be freed so as to move back and forth without obstruction, by means of the button W, which is pivotally secured directly in rear of the slide S, and has two flattened faces at different distances from its center, and either of which may be thrown in contact with the end of the slide, whereby the extent of the movement of the bar R and slide S may be controlled at will. When the slide S is drawn to the extreme of its forward movement, it carries the bar R with it and frees the oscillating levers M from any contact with the bolts B C, and said slide may be locked in this forward position by turning the button W, so that its flattened face X most distant from its center will come behind the same.

While the slide S, bar R, and levers M are in the position just described, the bolts B C may be moved freely by the knob-spindle alone, and the lock may then be employed as an ordinary latch. When, however, the button W is turned so that its face nearest the center comes in contact with the end of the slide S, the ends of the bar R will enter the notches N, and permit the spring Q to throw the rear ends of the levers M outward against the corresponding ends of the bolts B C, in which operation (the bolts being at their forward position) the lugs P on the levers M will pass behind the lugs I on the bolts B C, and thus serve to lock the said bolts until, by the operation

of the key from the outside of the door, as hereinafter described, the forward ends of the levers M are spread apart, so as to disengage the lugs I P, or until some one at the inside of 5 the door moves the slide S, and thereby moves the bar R forward, which has the same effect as the key, so far as the movement of the levers M is concerned.

Upon the forward portions of the levers M 10 are provided the corresponding lugs Z, which are arranged to be engaged by the two wings a of the key b, as hereinafter described.

Between the forward ends of the levers M, and immediately in rear of the bar R, are provided the standards c, connected at their base 15 by a cross-bar, d, the purpose of the standards being to receive the wards or combination of pieces e, said pieces being provided with notches f to rest over the cross-bar d. The 20 pieces e are provided, also, with notches g, which pass over the bar R, and the front ends of the said pieces terminate adjacent to the inner face of the cross-bar D, while their rear ends extend a suitable distance in rear of the 25 standards c, as shown. The pieces e are substantially the same, with the exception of their rear ends, which are cut to present when the pieces are in face-to-face contact an irregular upper surface, as shown in Fig. 3. The upper 30 edges of the rear ends of the pieces e are of varied height, and a portion or all of same are beveled. The pieces e may vary in thickness, or be otherwise different from each other, so that when their relations are altered from 35 that illustrated in the drawings a new key will be required to operate them. The set of pieces illustrated is but one of the many combinations or arrangements that may be devised, each necessitating alterations in the key 40 for moving its parts.

In Fig. 7 I illustrate the key which is employed for operating the series or combination of pieces e. It consists of the blade b and pivoted levers or wings a, the inner edges of which 45 parts a converge at a point adjacent to their pivots k, and have the inclined faces lettered l m, respectively. The lower ends of the wings or levers a project outward, as indicated, and are provided on their lower edges with wefts 50 n, when desired. When the lower ends of the levers a are together, the upper ends of the same will project beyond the side edges of the blade b, as indicated in Fig. 7, and when the upper ends of the levers a are moved toward 55 each other the lower portions of same will spread apart, as indicated by dotted lines in Fig. 7. The lower edge of the blade of the key is provided with wefts t, which pass over and engage the irregular surface formed upon 60 the rear portion of the series or combination of pieces e. It is plain that the wefts in the blade b must perfectly fit said irregular surfaces, otherwise only a portion of the pieces e will be affected by the key. A key-hole 65 guide or flattened sleeve, u, will be provided, in order that the key may be inserted from

the outside of the door, for the purpose of reaching the combination of pieces e and spreading apart the levers M. The sleeve u will be of slightly greater width than that of 70 the blade b, and when the key is to be inserted therein the lower ends of the wings a will be moved toward each other, so as to enter the sleeve, and when said key has been sufficiently inserted for the upper edge of the sleeve to 75 strike the outwardly-inclined upper portions of the wings a the lower ends of the said wings will be gradually forced outward from each other, and will come in contact with the projections or lugs Z on the levers M, and cause 80 the forward ends of the said levers to move outward, whereby they will release the cross-bar R and effect the disengagement of the lugs I P. The introduction of the key in the manner described also has the effect of engaging 85 the irregular surface presented by the upper rear ends of the combination of pieces e, and by pressing said rear portions the front ends thereof are elevated, so as to come directly opposite to the elongated slot E, formed in the 90 cross-bar D, connecting the two bolts.

When the elements of the lock are in the condition just described, it will be plain that the bolts may be moved into the casing A so as to unfasten the door by the rotation of the 95 knob-spindle. In the normal condition of the series e their forward ends are depressed by means of suitable springs, w, against the casing A in rear of the lower edge of the cross-bar D. When the rear ends of the pieces e 100 are depressed, their front ends will be elevated so as to be in line with the slot E and permit the movement of the bolts B C, as aforesaid. It will be obvious, however, that the key must be suitably constructed to properly 105 engage every one of the pieces e, for otherwise some of said pieces would either remain in their normal condition, or their front ends would ascend too far, and thus come in rear of the upper edge of the cross-bar D, while 110 others would possibly come in line with the slot. Thus it will be seen that the lock under such a condition of affairs could not be opened.

Hereinbefore I have described the condition of the parts of the lock when the same will 115 operate as an ordinary latch, which is when the slide S is drawn and secured at the end of its forward stroke. When the slide S is at the end of its back stroke, the lugs I P will be engaged and the front ends of the combination 120 of pieces e will be in rear of the lower edge of the cross-bar D, whereby the bolts B C will be doubly locked, for it is plain that to unfasten the door the lugs I P must be thrown apart, and at the same time the front ends of the combination of pieces e sufficiently elevated to pass 125 through the slot E. One of the series of pieces e has its lower rear edge resting upon the face of the casing A, so that when the key is inserted this piece being immovable, will arrest the key at the proper point to permit the 130 slot E to move over the front ends of the full

combination of pieces. When the slide S and bar R are moved forward, the combination of pieces e is elevated thereby, so as not to interfere with the proper movement of the bolts B C.

5 When the device hereinbefore described is used as a latch, the slide S need only be held forward until the lugs I P have passed each other and the combination of pieces e has entered the slot E, which occurs immediately after the bolts B C have been started inward from the nosing A'. Upon releasing the slide S (the bolts B C being on their back stroke) the spring Q forces the lugs P on the levers M in front of the lugs I on the bolts B C and moves (owing to the inclined faces in the notches N) the slide S back to its former position. The effect of this operation is that the bolts can only return forward about one-half their stroke, being prevented from further movement by the lugs P coming in front of the lugs I. When the door to which the lock is applied is being closed, however, the protruding ends of the bolts B C strike the nosing A' and are driven into the casing, and then 25 when the door is finally closed the spring J has sufficient force to cause the lugs I to pass the lugs P, whereby the bolts B C lock the door, and are themselves immediately deadlocked by the lugs B springing in rear of the lugs I. The lock is thus an automatic deadlocking latch.

It will be found very difficult to "pick" the lock described, for if the levers M are forced outward farther than the required distance, 35 their front ends will pass behind the shoulders B' and relock the bolts at this point. Thus even though the lugs I P become unlocked, the front ends of the levers and shoulders B' will secure the bolts under the condition specified.

40 The fact also that a portion of the combination of pieces e is beyond the sides of the key-hole will prevent any successful tampering with the lock.

To open the lock, the levers M must not only be properly spread apart, but it is also necessary that the combination of pieces e be successfully elevated. Thus one part of the lock acts as a check upon the other part until all parts are properly operated, which I consider impossible without the express key prepared by the manufacturer for the special lock to be opened.

The nosing A' is of the usual construction, with the exception of the pins G' on its edges 55 and the elongated screw holes D' at its ends. The pins C' when driven into the wood will hold the nosing in place until the lock may be tried or the screws applied, and the elongated screw-holes permit the nosing to be set nearer 60 the lock when the wood to which it has been secured has shrunk, and this without changing the hole made in the wood by the screw. The edges surrounding the elongated holes D' will be flat, and a screw having a head whose 65 under side is flat will be used in securing the nosing in place.

I reserve the right to adapt the lock for use upon doors, boxes, trunks, &c., and to modify the construction thereof within the scope of my invention.

70

What I claim as my invention, and desire to secure by Letters Patent, is—

1. In a lock, the bolts B C, connected at their front portion by a cross-bar, D, having an elongated slot, E, in combination with the 75 oscillating levers M, whose rear ends are adapted to engage the rear ends of the said bolts, the sliding bar R, arranged transversely between and to engage the front ends of the levers M, the slide S, located upon the outer 80 face of the casing A, and being in connection with the bar R, and a combination of pieces, e, arranged over the bar R and in line with the bolts B C, and adapted, when tilted, to permit the slot E to pass over them, substantially as set forth.

2. In a lock, the bolts B C, connected by a cross-bar, in combination with the oscillating levers M, the rear ends of which are adapted to engage the rear ends of the said bolts, and 90 with the sliding bar R, whose ends engage the front ends of the oscillating levers M.

3. In a lock, the bolts B C, connected by the bar D, and having upon their rear ends the lugs I, in combination with the oscillating 95 levers M, (one adjacent to each bolt,) having upon their rear ends lugs P, adapted to engage the lugs I on said bolts, and upon their front ends notches N, the sliding bar R, arranged transversely between the levers M, 100 and whose ends engage the notches N, and springs J Q, the former arranged to exert a tension forward on the bolts B C and the latter to throw the rear ends of the levers M into engagement with the rear ends of the bolts B 105 C, substantially as set forth.

4. In a lock, the bolts B C, connected by the bar D, and having upon their rear ends the lugs I, and forward thereof the shoulders B', in combination with the oscillating levers M, 110 the rear ends of which are adapted to engage the lugs I, the front ends of the levers being provided with notches N, and adapted to engage the shoulders B', and the sliding bar R, arranged transversely between the levers M 115 and in position to engage the notches N, substantially as set forth.

5. In a lock, the bolts connected at their front portion, in combination with a series of tilting locking-pieces, e, arranged in line with 120 the bolts, and a portion of the same being beyond the sides of the key-hole, and a key a portion of which will move outward when inserted into the key-hole and reach those pieces e beyond the sides thereof, substantially as 125 set forth.

6. In a lock, the bolts B C, connected by a bar, D, having a slot, E, in combination with the oscillating levers M, the rear ends of which are adapted to engage the rear ends of said 130 bolts, the sliding bar R, transversely arranged between and adapted to engage the forward

ends of the levers M, the combination of pieces e, arranged over said bar R, and a portion of which are beyond the sides of the key-hole, and a key having wings a a, which spread 5 apart after entering the lock and engage said pieces e beyond the sides of the key-hole, substantially as set forth.

7. In a lock, the bolts B C, connected by a bar, D, in combination with the oscillating 10 levers M, having lugs Z beyond the sides of the key-hole, the rear ends of the levers being adapted to engage the rear ends of said bolts, the sliding bar R, arranged transversely between, and whose ends engage the front ends 15 of the levers M, and the key b, having wings a a, which spread apart after entering the lock and strike the lugs Z, substantially as and for the purpose set forth.

8. In a lock, the bolts, in combination with a series of locking-pieces, e, a portion of which 20 are beyond the sides of the key-hole, and a key having wings a a, which spread apart when inserted into the lock and reach those pieces e beyond the sides of the key-hole, substantially as set forth.

25 9. In a lock, the connected bolts B C, levers M, bar R, and slide S, in combination with the button W, as described.

Signed at New York, in the county of New York and State of New York, this 30th day 30 of April, A. D. 1884.

BENJAMIN MOSER.
